UNITED STATES PATENT OFFICE

EDMUND SCHULTE, OF BRONXVILLE, NEW YORK

DESIGN FOR A GATEWAY

Application filed December 27, 1929. Serial No. 33,947. Term of patent 3½ years.

To all whom it may concern:

Be it known that I, EDMUND SCHULTE, a citizen of the United States, residing at Bronxville, in the county of Westchester and State of New York, have invented a new, original, and ornamental Design for Gateways, of which the following is a specification, reference being had to the accompanying drawing, forming part thereof.

In the drawing—

Figure 1 is a front elevation of a gateway, showing my new design, the ornamentation shown being continued throughout; and

Figure 2 is an enlarged transverse sectional view substantially on the line 2—2 of Figure 1.

I claim:

The ornamental design for a gateway, as shown and described.

EDMUND SCHULTE.
